Primary Examiner — Deanna L Pratt*(74) Attorney, Agent, or Firm* — Faegre Drinker Biddle & Reath LLP(57) **CLAIM**

The ornamental design for a lounge, as shown and described.

DESCRIPTION

FIG. 1 is a front perspective view of a lounge;

FIG. 2 is a front view thereof;

FIG. 3 is a rear view thereof;

FIG. 4 is a side view thereof; and,

FIG. 5 is a top view thereof.

The evenly spaced broken lines illustrate portions of the lounge that form no part of the claimed design. The unevenly spaced broken lines illustrate the bounds of the claim and form no part thereof.

1 Claim, 5 Drawing Sheets(56)
